UNITED STATES PATENT OFFICE.

HENRY J. GILBERT, OF SAGINAW, MICHIGAN, ASSIGNOR TO MISSISSIPPI GLASS COMPANY, A CORPORATION OF NEW YORK.

DESIGN FOR SHEET-GLASS.

40,261.

Specification for Design.

Patented Sept. 14, 1909.

Application filed July 6, 1907. Serial No. 382,553. Term of patent 14 years.

To all whom it may concern:

Be it known that I, HENRY J. GILBERT, a citizen of the United States, residing at Saginaw, in the county of Saginaw and State of Michigan, have invented a new, original, and ornamental Design for Sheet-Glass, of which the following is a specification, reference being had to the drawing accompanying and forming a part of the same.

In the drawing, the figure is a plan view of a sheet of glass, showing my new design.

In my design the glass sheet is provided with parallel ribs or ridges, and the ribs or ridges themselves are crossed by diagonal grooves.

What I claim is:

The ornamental design for sheet glass, as shown.
